UNITED STATES PATENT OFFICE.

THOMAS RICHARD CANNING, OF BIRMINGHAM, ENGLAND.

ELECTROPLATING APPARATUS.

1,020,262.

Specification of Letters Patent. Patented Mar. 12, 1912.

Application filed February 23, 1911. Serial No. 610,396.

To all whom it may concern:

Be it known that I, THOMAS RICHARD CANNING, a subject of the King of Great Britain, residing at 135-137 Great Hampton street, Birmingham, Warwickshire, England, have invented new and useful Improvements in Electroplating Apparatus, of which the following is a specification.

This invention relates to an electro-plating apparatus specially intended for dealing with small quantities of work at one time, without the necessity of wiring the articles in the usual manner.

The improved apparatus consists mainly of a perforated earthenware or other non-metallic receptacle for holding the articles to be plated, of a holder for carrying the said receptacle immersed in the bath, and of means for rotating the said holder, the whole apparatus being designed to be fixed on the wall of an ordinary wooden or other plating vat.

In a suitable form of apparatus I provide a bracket which may be fixed to the plating vat by means of, say, coach screws or bolts and which is provided with an inclined bearing in which the rotary spindle for carrying the receptacle is mounted, and a bearing for a horizontal driving spindle having upon it fast and loose pulleys and a worm engaging with a worm-wheel on the upper end of the inclined spindle. The lower end of the inclined spindle carries arms supporting in bearings an insulated metal ring holding the basket or receptacle and which can swing freely upon a horizontal axis.

To enable the invention to be fully understood, I will describe the same by reference to the accompanying drawing, in which:

Figure 1 is a sectional side view of the improved apparatus applied to the wall of an ordinary depositing tank or bath, and Fig. 2 is a plan of the same.

Fig. 1 indicates the tank and b the bracket adapted to be fixed upon the same for carrying the improved apparatus, the said bracket being provided with an inclined bearing c for the carrying spindle d. The said bracket is also formed with bearings e, e for the driving shaft f which is provided with fast and loose pulleys g, g' and has fixed to it a worm h engaging with a worm-wheel i on the upper end of the said spindle

d. To the lower end of the spindle d is fixed a boss j to which arms k, k are fixed but insulated therefrom.

l is the perforated earthenware or other non-metallic receptacle for containing the articles to be plated, the said receptacle having formed integral with it a handle m for facilitating the handling thereof. This receptacle l, which is flanged at its upper edge, is carried in a metal ring n provided with an insulating covering o to prevent it from corroding, the said ring n being provided with trunnions p, p carried in bearings q, q at the ends of the arms k, k so that the ring can swing therein. These trunnions p, p have also fixed to them arms r, r at the free end of which are arranged sliding spring pins s, s, the inner ends of which are adapted to lock into holes or notches formed in the arms k, k for the purpose of retaining the receptacle l in the inclined position with respect to the bath as indicated.

The disengagement of the pins s, s from the arms k, k allows of the receptacle l swinging to an upright position as indicated by the dot and dash lines in Fig. 1, so that the receptacle can be readily lifted out of the ring n and replaced.

t is the metallic wire for carrying the negative current, this wire being connected to a terminal u fixed upon the handle m of the basket, the said terminal being formed with a clip v provided with a thumb-screw v' for readily connecting it with the wire w attached to the boss j.

With this arrangement it will be understood how the receptacle l can be readily introduced and removed by operating the spring pins s, s and the clip v. Instead of two spring pins s, s one only may be employed.

It will be understood that other means than those described may be employed for connecting the receptacle l to the spindle d, for instance, the arms k, k may be provided at their extremities with hooks or slots with which lugs on the ring n may be engaged, in which case the receptacle with the ring upon it would be disengaged from the said arms while in the inclined position.

The improved apparatus serves not only for electro-plating articles, but also for polishing.

Having now particularly described and

ascertained the nature of my said invention and in what manner the same is to be performed, I declare that what I claim is:—

1. In an electro-plating apparatus the combination with an inclined spindle carried in a bearing adapted to be fixed to the wall of an electro-plating tank, of means for rotating said spindle, and of a receptacle mounted on the lower end of said spindle in such manner that it can be readily detached therefrom.
2. In an electro-plating apparatus the combination with an inclined spindle carried in a bearing adapted to be fixed to the wall of an electro-plating tank, of means for rotating said spindle, of arms secured to said spindle, of a ring pivoted to said arms, and of a receptacle carried by said ring in such manner that it can be readily detached therefrom.
3. In an electro-plating apparatus the combination with an inclined spindle, car-

ried in a bearing adapted to be fixed to the wall of an electro-plating tank, of means for rotating said spindle, of arms secured to the lower end of said spindle, of a ring pivoted to said arms and capable of a relative movement thereto, and of a receptacle carried in said ring.

4. An electro-plating apparatus comprising a bracket provided with a plurality of bearings, a shaft provided with a worm mounted in one of said bearings, a spindle mounted in the other of said bearings, said spindle being provided with a worm wheel which meshes with said worm, arms secured to said spindle, a ring pivoted in said arms and capable of movement relative thereto, and a receptacle carried by said ring.

THOMAS RICHARD CANNING.
